US0D1069121S

(12) **United States Design Patent** (10) **Patent No.:** **US D1,069,121 S**
(45) **Date of Patent:** **** Apr. 1, 2025**

(54) **PEDICLE SCREW**

(71) Applicant: **Curiteva, Inc.**, Tanner, AL (US)

(72) Inventors: **Eric Linder**, Dublin, OH (US); **Ryan Heskett**, Wellington, FL (US)

(73) Assignee: **Curiteva, Inc.**, Tanner, AL (US)

(**) Term: **15 Years**

(21) Appl. No.: **29/840,847**

(22) Filed: **Jun. 1, 2022**

(51) LOC (15) Cl. **24-02**

(52) U.S. Cl.

USPC **D24/171; D8/387**

(57) **CLAIM**

The ornamental design for a pedicle screw, as shown and described.

DESCRIPTION

FIG. 1 is a top perspective view of a pedicle screw showing our new design;

FIG. 2 is a bottom perspective view thereof;

FIG. 3 is a front view thereof;

FIG. 4 is a right view thereof;

FIG. 5 is a rear view thereof;

FIG. 6 is a left side view thereof;

FIG. 7 is a top view thereof; and,

FIG. 8 is a bottom view thereof.

The broken lines indicate portions of the pedicle screw that form no part of the claimed design.

1 Claim, 7 Drawing Sheets
